UNITED STATES PATENT OFFICE.

HIRAM W. COOLEY, OF CHICAGO, ILLINOIS.

DOOR LATCH.

Application filed November 24, 1923. Serial No. 676,691.

This invention relates to a door latch designed primarily for latching a pair of swinging doors such as are usually put upon the rear end of the closed body of a vehicle.

It is an object of this invention to provide a simple latch that is readily actuatable and that firmly holds the doors in closed position and prevents rattling.

With these and other advantages in view which will become more apparent in the following description and disclosures, this invention comprises the novel mechanism and combinations hereinafter described and more particularly pointed out and defined in the appended claims.

In the accompanying drawings which illustrate a preferred embodiment of this invention and in which similar reference numerals refer to similar features in the different views.

On the drawings:

Figure 1 is a top plan view of the latch.

Figure 2 is an enlarged section upon the line 2-2 of Figure 1, showing the latch applied to a pair of doors.

Figure 3 is a reduced section through the doors showing the latch in elevation.

Figure 4 is a sectional view upon the line 4-4 of Figure 1 with the latch applied to a door.

Figure 5 is a view upon the line 5-5 of Figure 2.

As shown on the drawings:

In referring now to the drawings the reference numeral 1 illustrates a latch bar which is hinged upon one door 2 and overlaps the other door 3 to which it is removably secured. The latch bar is in the form of a channel having lateral flanges connected by an outer web. The rear end of the latch slopes outwardly and is provided with an arcuate terminal which fits over a V or inverted channel shaped supporting hinge member 4 having an arcuate outer surface, which is bolted to the door 2; a pivot pin 5 extending through the lateral flanges of the latch bar and through the sides of the hinge member 4 for hinging the latch bar to said door. The web of the inverted channel 4 extends forwardly and is bent outwardly in the form of a spring or resilient tongue 4a.

A parti-circular disk 6 is rotatably mounted upon the forward end of the latch bar. The plan view of this disk is shown in Figure 5. It consists of a disk having an arcuate portion somewhat greater than 180

degrees and which terminated in a straight stop ridge or rib 7. The central part of the arcuate portion is raised and slopes downwardly to the ridge 7 as is shown in Figure 60 2. The disk 6 is fastened upon the shank 8 of an operating handle 9 which is rotatably mounted upon the latch bar. If desirable the disk 6 may constitute an integral part of the shank. The forward part of the 95 latch bar is provided with a slot 10 for receiving a locking hasp 11 secured to the door. This hasp has a forwardly projecting nose or lug under which the disk 6 is adapted to be rotated, and is provided with an aperture 70 for receiving the hasp of a padlock or seal for locking the doors when desired.

In the position shown in Figures 2 and 5, the latch bar 1 is in latching position with the edge of the disk 6 under the nose of the 75 hasp 11 and the spring 4a confined under tension between the door 2 and the latch bar. If it is now desired to open the doors the disk 6 is rotated until the rib 7 has moved through an arc of 180 degrees; the rib 7 passing under the nose of the hasp 11 through an inward pressure of the latch bar if necessary. Such an operation will bring the ridge 7 adjacent the front point of the hasp 11 so that the latter can pass through the slot 10 as the latch is swung outwardly upon its pivoted hinge connection 5. In case there should be an accidental rotation of the disk 6 as when the vehicle is going over rough roads the spring 4a will maintain the latch 80 against the nose of the hasp 11 and the ridge 7 will act as a stop to prevent the locking disk 6 from rotating to inoperative position. In latching the doors, they are 85 swung into closed position, so that their adjacent ends abut the upright 12 when the latch 1 may be swung over the hasp 11 and the disk rotated to locking position under the nose of the hasp.

It should be noted that the spring 4a is 100 housed and concealed within the channel-like member and that the rotatable cam disk 6 has integral stops in the ridge 7 to prevent the same from accidentally rotating into an inoperative position and releasing the doors. 105 Consequently an extremely simple and efficient latch has been provided which conceals the supporting means therebeneath and presents a neat and pleasing appearance.

I am aware that numerous details of construction may be varied through a wide range without departing from the principles 110

of this invention, and I therefore do not purpose limiting the patent granted otherwise than necessitated by the prior art.

I claim as my invention:

- 5 1. A door latch comprising a channel-shaped member, a support embraced by the lateral flanges of said member, said support having a forwardly projecting spring tongue and a parti-circular cam disk rotat-
- 10 ably mounted upon said latch and having stop ridges for the purpose set forth.

2. A door latch comprising a channel-shaped member, a support to which the same is pivotally mounted, said support having a forwardly extending spring tongue, and a ¹⁵ rotatable cam disk upon said latch embodying stop ridges, said latch having a slot adjacent said disk for receiving a latching hasp.

In testimony whereof I have hereunto subscribed my name.

HIRAM W. COOLEY.
